UNITED STATES PATENT OFFICE.

WILLIAM F. CLAYTON, OF HUNTSVILLE, ALABAMA, ASSIGNOR OF ONE-THIRD TO
ROBERT E. SMITH, OF HUNTSVILLE, ALABAMA.

THIN-PLACE DETECTOR.

Application filed February 7, 1922. Serial No. 534,803.

To all whom it may concern:

Be it known that I, WILLIAM F. CLAYTON, a citizen of the United States of America, residing at Huntsville, in the county of Madison and State of Alabama, have invented certain new and useful Improvements in Thin-Place Detectors, of which the following is a specification.

My invention relates to improvements in means for detecting the presence of thin places in fabrics and for automatically removing such defects.

The general object of my invention is the provision of means for the automatic control of the operation of a loom, by which means the loom is kept in continuous operation and thick and thin places in the finished weave are prevented.

An object of my invention is the construction of a device which will detect, after a certain predetermined number of picks, a thin place in a fabric while it is being woven.

A further object of my invention is to raise the arm of the thin place detector after the point thereof has fallen through the thin place and has thus started the operation of my improved mechanism which fills in the thin place.

Another object of my invention is to provide means whereby the detector arm will be returned to its normal position a predetermined time after the weaving is re-started.

Another object of my invention is the construction of a device which will operate only when the filling fork fails to operate.

A still further object of my invention is the construction of a device which may be used on the ordinary Draper loom without removing the filling fork which is used on that loom.

This invention is an improvement of the structure described and claimed in my application Serial No. 471,892, filed May 23, 1921.

With these and further objects in view, I have presented in the drawings one embodiment of my invention, in which drawings:

Figure 1 is a top plan of a part of my device, showing its position on the fabric in the process of weaving and its connection with the starting rod.

Figure 2 is a side elevation of the thin place detector arm and some of its parts;

Figure 3 is a section on the line 3—3 of Figure 1;

Figure 4 is a side elevation of the take-up ratchet wheel and associated parts;

Figure 4^a is a side elevation of the end of a modified form of detent carrier.

Figure 5 is a top plan of the detent and carrier.

Figure 6 is a side elevation of the snake head with my improved brass attached thereto;

Figure 7 is a modified form of the part which is placed above the snake head;

Figure 8 is an edge view of a device to be used with a loom equipped with a double filling fork;

Figure 9 is a view at a right angle to the view shown in Figure 8; and

Figure 10 is a bottom plan view of the device disclosed in Figure 8.

My invention is shown attached to the usual Draper loom, such as shown in the patent to Northrop, No. 529,940, and having the usual breast beam 1 and starting rod 2, corresponding to the beam A¹⁰ and rock shaft d' of that patent.

The essential parts of my invention are a thin place detector, a lifter for the detector, a let-back device for the take-up ratchet wheel, and connections whereby the detecting action of the detector will set in operation the let-back device, the lifter, and the usual filling replenishing means.

The detector comprises a rod 3, attached to the breast beam 1. A part 4, extending at right angles to one end of rod 3, carries

the usual resilient head or finger 5, of the same general character as the head shown in my application Serial No. 471,892, filed May 23, 1921, mentioned above.

A coil spring 6, around the part 4, presses the loose

collar 7 against the head 5, while the tension of the spring is adjusted by means of a collar 8 held in position by a set screw 9.

Movement of the cloth contacting point of the finger 5 away from the breast beam 1 is limited by contact of the collar 7 with a notch 10 in the head.

The end of rod 3 opposite part 4 terminates at the filling fork side of the loom, and carries an extension 11. The extension 11 is

in a plane parallel with part 4, but at a different angle in the plane, so that when part

4 is substantially horizontal, as shown in

Figure 2, extension 11 will extend upwardly as shown in Figure 3. The part 11 extends through a loop 15, connected to a pawl 16. The pawl 16 is pivoted at one end to a rock 5 arm on the starting rod, as will be described later. When the finger 5 rests on the cloth, the pawl 16 is held in inoperative position; but when the finger drops through a thin place, the end of the pawl is lowered into operative relation to a special form of brass 17 on the usual snake head 17^a of the loom. The pawl is then moved lengthwise, rocking the arm to which it is attached, and also raising the finger free from the cloth by the means now to be described.

A rod 18 consists of a part 18^a and a part 18^b at right angles to the part 18^a. It will be apparent that the part 18^a normally rests on the base of the loop 15. The part 20 18^b is attached to the breast-beam by means of loops 19 and 19^a through which it passes. These loops are placed above attaching loops for the rod 3, the loops for both rods being attached by the same screw 19^c. The 25 rod 18 is adjustably attached to a casting 20 by insertion in an opening therein and in which it is held by a set screw 21.

An arm 22 which is an integral part of the casting 20, and extends substantially 30 parallel with the finger-supporting part 4, has a right-angled extension 23 through which is a slot 24 for the part 4. To this arm is pivotally attached an adjustable supporting member 30 having a roughened foot 30^a to enable it to act on the cloth. It may be adjusted as to height by a slot 31. The top of this member has a weighted head 32 which tends to swing the lower part of the member towards the fell against an adjustable stop 33. Another adjustable stop, 34, serves as a limit to the swing of this member in the opposite direction. Stops 33 and 35 34 are, preferably, separate pieces having holes in their ends which are slipped over the pivot of member 30, and are adjusted upward and downward with the adjustment of that pivot in slot 31, and are secured in adjusted position about the pivot when it is tightened in adjusted position in the slot. 40 It will be apparent that when the pawl 16 is pressed backward, the rod 18 and attachments will raise the resilient head from the cloth.

In Figure 7 is shown an alternative form 45 of pawl, 16^a. By use of this form of pawl the finger lifting device so far described may be applied to a loom having the thin place detector of the Clayton and Bentley Patent No. 828,534, granted August 14, 50 1906. When the arm 22 is raised the foot of the supporting member is urged towards the fell by the weight 32, and as the foot is approximately concentric with the axis of its pivot, it will hold the arm 22, and 55 through it the finger or head, in raised po-

sition as long as any portion of the foot is vertically beneath the pivot. The distance the cloth moves while the finger is held raised depends upon the adjustment of stop 33.

As before stated, the pawl 16, when the head 5 drops through a thin place, is carried down and engages with a special form of brass 17 attached to the usual form of snake head 17^a by which the parts are carried back to the positions indicated in dotted lines in Figures 2 and 3. The pawl 16 is pivotally connected to an attaching device 37 which is held in adjusted position in an arm 38 by a set screw 38^a. The pivot of pawl 16 being eccentric to the pin 37^a of the device 37 allows the adjustment of the pivot of the pawl up, down, forward, backward or laterally. The arm 38 encircles the starting rod 2.

On one side of the arm 38 where it surrounds rod 2 is a collar 39 held in position by a set screw 40. On the other side of the arm is a collar 41 held in position by set screw 42. A tooth 43 on collar 41 operates with a tooth 44 on the arm 38. The teeth are so related that the rod may rock on the normal operation of the machine without contact of the teeth, but when arm 38 is rocked the teeth contact and cause 55 rocking of the rod to start the automatic filling replenishing device.

The arm 38 has a threaded opening receiving the threaded end of a rod 38^b which is locked in adjusted position by lock nut 100 38^c. The outer end of rod 38^b is bent downward, and to its lower end there is attached a finger 45.

A detent 46, take-up pawl 47, and take-up ratchet wheel 48 are shown somewhat 105 diagrammatically, they being conventional parts of a Draper loom. The free end of the finger 45 moves in a slot in detent 46, and when the arm 38 is rocked, the detent 46 is raised and in turn raises the take-up 110 pawl 47, so that the take-up ratchet wheel 48 is freed from its operating devices.

Where one or more let-back pawls or 115 detents are provided to let back the take-up wheel in the ordinary operation of the filling fork, means are provided whereby the oscillation of arm 38 will release these let-back detents as well as the take-up pawl and detent. As this releasing means can be supplied without invention and will depend upon the type of let-back pawl used, 120 it is not shown.

When freed by the action of arm 38 from 125 all pawls and detents controlling its normal operation, the take-up ratchet wheel is let back a definite distance by the following devices:

A detent carrier 50 is pivoted concentrically with the take-up wheel 48. A detent 51 is pivoted at 52 to the carrier 50, and 130

a weight 53 is connected to the detent to urge it into engagement with the wheel 48. The carrier 50 is weighted at 54 so that the detent follows the take-up motion of the wheel until the carrier encounters a stop. As shown, the carrier encounters the pinion 55 of one of the gears connected to the wheel, but an adjustable stop might be substituted if desired. Ordinarily the carrier is fixedly weighted, as shown in Figure 4, but if desired a sliding weight, 56, may be substituted, as shown in Figure 4^a, and fixed in adjusted position on the carrier by a set screw, 57.

The detent pivot 52 is extended, as shown at 58 in Figure 5. A stop, 59, is fastened to the frame of the machine, preferably adjustably, as by means of bolts 60, 61, passing through slots 62, 63. The end, 64, of the stop extends into the path of the extension 58, and when the take-up wheel is freed, by the movement of arm 38, from its normal operating devices, it is let back a definite distance depending upon the distance between the normal position of the detent 51 and its position when the stop end 64 is encountered. It is evident that instead of having the stop 59 fastened by two bolts, it may be adjustably fastened by using one bolt.

To use my invention on a loom having a double filling fork, such as the loom known as the Draper "J. Model", it is necessary to utilize the improvement disclosed in Figures 8, 9 and 10. To the shank or lever 70 of the snake head as used on a Draper loom, there is attached an improved lever 71 by means of a base 72 clamped by a bolt 73 around the shank 70. My improved lever reaches above the usual form of the brass of the snake head 17^a, and has at the top thereof a new form of snake head 74 with which the lever 16 engages when my improvement is used with a loom having a double filling fork. A part of the conventional filling fork slide 75 is shown in Figure 9 for the purpose of indicating the position of the improved lever. This feature is more fully disclosed in my co-pending application Serial No. 471,892, filed May 23, 1921.

The operation of the invention has been referred to in connection with the description of its various parts, and detailed description of its operation is unnecessary. It will be clear without such detailed description that I have invented a finger raising device which may be readily applied to a machine equipped with a thin place detector such as shown in the Clayton and Bentley patent; that I have provided a support for the finger raiser that may be applied to any finger raising arm and may be adjusted for holding the arm raised a defi-

nite distance during the desired extent of movement of the cloth; that I have provided a let-back device capable of allowing any desired extent of let-back without any material change in the relation of the let-back detent to the ratchet-wheel; and that when my improved devices are used together a device is provided which will detect a thin place, let back the cloth the exact number of picks necessary to remedy the faulty action of the loom, start the automatic filling-replenishing device, raise the detector out of contact with the cloth to allow the let-back, and maintain it raised the exact number of picks desired before it resumes its detecting position.

What I claim is:

1. In a loom, a moving member, a thin place detector comprising a finger normally resting on the cloth adjacent to the fell, a pawl, and connections between the finger and pawl holding the pawl in inoperative position while the finger rests on the cloth and allowing the pawl to engage the moving part when the finger drops, a finger raiser having a portion in the path of the pawl and a portion over the cloth, and means rigidly connecting said portions and a lost motion connection between the portion over the cloth and the finger.

2. In a loom, a moving member, a thin place detector comprising a finger normally resting on the cloth adjacent to the fell, a pawl, and connections between the finger and pawl holding the pawl in inoperative position while the finger rests on the cloth and allowing the pawl to engage the moving part when the finger drops, a finger raiser having a portion in the path of the pawl and a portion over the cloth and means rigidly connecting said portions, a lost motion connection between the portion over the cloth and the finger, and a supporter pivoted to the finger positioning devices above the cloth and on an axis parallel to the fell.

3. In a loom, a thin place detector comprising a finger normally resting on the cloth, an arm connected to the finger, and a supporter pivoted to the arm on an axis parallel with the fell and having an extended foot concentric with its axis.

4. In a loom, a thin place detector comprising a finger normally resting on the cloth, an arm connected to the finger, and a supporter pivoted to the arm on an axis parallel with the fell and having an extended foot concentric with its axis, the bottom of the foot being roughened.

5. In a loom, a thin place detector comprising a finger normally resting on the cloth, an arm connected to the finger, a supporter pivoted to the arm on an axis parallel with the fell and having an extended foot concentric with its axis, means urging

the foot towards the fell, and an adjustable stop limiting the swing of the foot towards the fell.

6. In a loom, a thin place detector comprising a finger normally resting on the cloth, an arm connected to the finger, means set in operation by the dropping of the finger to cause the arm to raise the finger above the cloth, and a supporter pivoted to the arm on an axis parallel with the fell and having an extended foot concentric with its axis.

7. In a loom, a thin place detector comprising a finger normally resting on the cloth, an arm connected to the finger, means set in operation by the dropping of the finger to cause the arm to raise the finger above the cloth, a supporter pivoted to the arm on an axis parallel with the fell and having an extended foot concentric with its axis, means urging the foot towards the fell, and an adjustable stop limiting the swing of the foot towards the fell.

8. In a loom, a thin place detector comprising a finger normally resting on the cloth, an arm, lost motion connections between the arm and finger, means set in operation by the dropping of the finger for causing the arm to raise the finger, and a

support pivoted to the arm on an axis parallel with the fell and having an extended foot concentric with its axis.

9. In a loom, a thin place detector comprising a finger normally resting on the cloth, an arm, lost motion connections between the arm and finger, means set in operation by the dropping of the finger for causing the arm to raise the finger, a support pivoted to the arm on an axis parallel with the fell and having an extended foot concentric with its axis, the bottom of the foot being roughened, and a stop limiting the swing of the foot.

10. In a loom, a thin place detector comprising a finger normally resting on the cloth, an arm, lost motion connections between the arm and finger, means set in operation by the dropping of the finger for causing the arm to raise the finger, a support pivoted to the arm on an axis parallel with the fell and having an extended foot concentric with its axis, a stop limiting the swing of the foot, and an adjustable let-back device adapted to let back the cloth a distance corresponding to the swing of said foot when the detector operates.

In testimony whereof I affix my signature.
WILLIAM F. CLAYTON.
